UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,161,541.

Specification of Letters Patent. Patented Nov. 23, 1915.

Application filed April 25, 1913. Serial No. 763,532.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to the type actions of such machines.

My invention has for its principal object to provide an improved type bar action, 15 especially for visible typewriters.

One of the improvements consists in making the mechanism easier to assemble, the assembling of whole sets of the mechanism being done outside of the machine, and each 20 of said sets of mechanism and its support being capable of insertion into the machine as an entirety. I have also had in mind to make the mechanism of a sort that is inexpensive to manufacture and yet durable, 25 convenient and efficient in use—to make it at once good and inexpensive.

I have also had other objects in view which will appear hereinafter.

To the above ends my invention consists 30 in certain features of construction and combinations and arrangements of parts, all of which will be fully set forth herein and particularly pointed out in the claims.

In the accompanying drawings, Figure 1 35 is a front to rear vertical sectional view of enough of a typewriting machine to illustrate the embodiment of my invention therein. Fig. 2 is a fragmentary view similar to part of Fig. 1 but on a section taken nearer 40 to the left-hand side of the machine. Fig. 3 is a front view in vertical section a little in front of the type bar segment, the platen being indicated in broken lines. Fig. 4 is a top plan view partly in horizontal 45 section below the type bar segment, and this view being partly diagrammatic in its character. Fig. 5 is a more or less fragmentary view showing the type bar segment shifted to its upper position and one of the middle 50 type bars in printing position. Fig. 6 is a similar view but showing the segment in its lowest position.

All of the figures of the drawing are on a reduced scale.

55 The main frame of the machine shown in

the drawings, comprises a base part 1, corner posts 2 and two frame bars 3, each of which connects the top of one of the front posts 2 with the top of the corresponding back post 2. Each of these bars is formed 60 with a U-shaped part 4, Fig. 1, to accommodate the rails and other devices not shown herein but associated with a carriage in which is mounted a platen 5. The two bars 3 are connected in the forward part of the machine by a front top plate 6 and in the rear part by another top plate 7. The plate 6 is formed with two side plates between 65 which is a well or opening for the type bars to strike up through and said side plates are 70 connected across the front of said opening by an integral cross bar 8.

The type action comprises printing keys 10 mounted on the forward ends of key levers 11 of the first order, which are pivoted on fixed pivot rods 12, one rod for each of the three banks of keys, and which at their rear ends are connected by upright links 13 with sub-levers 14 which in turn are connected by links 15 with front strike 75 type bars 16. The construction is such that when one of the keys 10 is depressed the corresponding link 13 is pushed upward, 80 rocking the sub-lever 14 and causing the link 15 to pull toward the rear on the type bar 16, throwing it to the printing point. In the present instance, each of the type bars has three types 17 thereon, and the segment 18 which constitutes the shiftable support of said type bars, is capable of being 85 shifted from the normal middle position shown in Fig. 1 to either of two shifted positions shown respectively in Figs. 5 and 6.

The three stationary rods 12 on which the key levers 11 are mounted, extend crosswise 90 in the base of the machine as shown in the drawings, the levers being spaced apart on each rod by sleeves 19, Fig. 3. These rods 12 are mounted at their ends in brackets 95 extending upward from a transverse frame bar 21 secured by means of screws 22, Fig. 4, to the two side bars of the base 1 of the mainframe. The construction is such that this cross bar 21, with the three rods 12 and the whole system of printing key 100 levers, can be removed from the machine as an entirety by removing the screws 22; and in the manufacture of the machine these parts can all be assembled outside of the 105 machine and placed in the machine as an 110

entirety. The mechanism that can thus be assembled outside and put into the machine as a whole, also includes other devices in addition to those above mentioned. As here shown, each rod 12 has each of its ends bearing against the inner face of a bracket 20 and secured in place by a screw 23, as shown in Fig. 3. The construction is such that in assembling the machine the key levers 11 and sleeves 19 are strung along the rod 12, which is then inserted between the two brackets 20 and secured in place by the screws 23.

The keys 10 are arranged in three rows, as is usual in typewriters in which there are three types on each type bar, and of these the rear row is the highest and the front row lowest, as is also usual. All of those key levers 11 whose keys are in the rear row are pivoted on the rearmost one of the three bars 12; those key levers whose keys are in the middle row are pivoted on the middle one of said bars, and those whose keys are in the front row are pivoted on the forward one of said rods, this arrangement being of course for the sake of uniformity of leverage, said rods being so disposed that all of the keys 10 have substantially the same leverage on their respective links 13.

In addition to placing the rods 12 one in front of another, I have also placed them at different elevations corresponding to the different elevations of the several rows of keys 10. I have placed these rods thus in order that all of the keys 10 may have not only the same extent of motion but also the same direction of motion. I prefer in this respect the arrangement shown in Fig. 1, where each of the rods 12 has its center a little below the upper surfaces of the corresponding keys, when said keys are in normal position, and a little above the upper surface of any one of said keys when said key is in its depressed position. With the rods 12 disposed in this manner, each of the keys 10 has a substantially vertical motion. Typewriter key levers have usually heretofore been pivoted all on the same level, the pivots being usually in a lower plane than the keys. The result of this construction has been that the keys have had a motion, not vertical, but in a path downward and somewhat inclined toward the front of the machine, and the keys in the rear row have moved in paths more sharply inclined toward the front than those of the forward row. By the arrangement shown, all of the keys move, as was said above, in substantially vertical paths. This feature of arranging the fulcrum rods 12 in the different elevations as described, is not essential to the success of the other features of my invention, but I consider it to be of advantage.

As the system of type bars is narrower than the system of keys, the key levers 11

fan in toward the rear of the machine as indicated in Fig. 4, that is to say, said key levers are a little closer together at their rear ends than at their forward ends.

Returning springs 24 for the key levers 70 are shown connected with the rear ends of said levers and to a series of hooks 25 suitably formed on the lower edge of a thin plate 26, which plate is riveted to a thicker plate 27 which is secured by screws 28 to 75 the back plate of the base 1 of the frame. As shown in Fig. 3, the screws 28 pass through slots 29 so as to make the compound plate 26, 27 adjustable up and down to regulate the tension of the springs. 80

The links 13 are preferably so formed as to be readily disconnectible. The lower parts of the type action, including the key levers, are assembled separately from the upper part and it facilitates the manufacture of the machine to have these links 85 readily disconnectible.

The type action is so designed as to afford what is commonly called in the art an "accelerated motion" to the type bar, that is to say, the leverage of the type bar on the key is substantially greater at the end of the key stroke than it is at the beginning of the key stroke. This is due in the present instance mainly to two things. In the first place, the rearwardly extending arms of the sub-levers 14, normally stand a little above the horizontal, as shown in Fig. 1, so that even at the beginning of a key stroke the motion of the upper end of the link 13 is at an inclination 95 toward the front of the machine, and the lever arm of said link, measured from the wire 30 perpendicularly to said link, diminishes constantly during the stroke until at the end of said stroke, as shown in Figs. 5 and 6, said lever arm is materially shorter than at the beginning of the stroke; but even at the end of the stroke said lever arm is still of a substantial length. The second cause of the so-called acceleration is found 100 in the disposition of the other arm of said lever 14, which arm normally extends downward and toward the front of the machine, as indicated in Fig. 1, and at the end of a key stroke this arm extends not very far 105 from vertically. The result is that the lever arm of the lever 14 on the link 15, is shortest when the parts are in normal position, (though it is of substantial length, even then) and is about at its maximum when the 110 type bar is at printing position. There are thus two sources of acceleration and they are so related that the final change in leverage between the key and the type bar, is equal to the product of the change due to 115 the changing leverage of the lever 14 on the link 13 multiplied by that of said lever on the link 15. In the layout shown in the drawings the leverage of the type bar on the key is in the neighborhood of three 120

times as great at the end of the key stroke as it is when the parts are in normal position.

The sub-levers 14 may be mounted and arranged in any one of a variety of ways. For example, the said sub-levers can be arranged in the arc of a circle to correspond with the arc of the type bars, but under those conditions the links 15 would be of different lengths. In the present instance, however, I have shown the sub-levers arranged in a straight row and all pivoted on a straight pivot wire 30 seated in a groove 31 in the rear face of a cross bar 32, said cross bar being formed at its rear side also with a series of vertical slots in which the sub-levers are guided. The links 15 are connected with the type bars above the pivots of the latter, and said links extend from the sub-levers 14 at various inclinations to the horizontal, as will be understood from Figs. 1 and 3, those links that connect with the middle type bars having a slight downward inclination and those connected with the end type bars of the system having about the same degree of upward inclination. In Fig. 1 two type bars and their connecting links 15 are shown, one being at the extreme left-hand end of the system and the other at about the middle of the system. It will be noted that in this figure, which shows the parts in normal positions, the link 15 that is connected with the middle type bar makes a more obtuse angle with the sub-lever 14 than that link 15 which is connected with the end type bar. In other words, the lower arms of the sub-levers 14 are normally more nearly perpendicular to those links 15 near the ends of the system than to those links 15 near the middle of the system. It will be obvious, therefore, that when the keys are operated those type bars near the middle of the system will have a higher acceleration than those near the ends of the system. The initial leverage of the key on the type bar is greater near the middle of the machine than near the sides of the machine. This is as it should be, because those type bars near the middle of the segment, when they are first set in motion, are moving more directly against gravity than those near the sides of the system, which latter move upward at a considerable inclination to the vertical. The effect of this arrangement in the present instance is that the touch seems to be substantially uniform throughout the system.

As far as my invention is concerned, the type bars can be pivoted in the segment 18 in any suitable manner. As here shown the rear part of said segment is formed with radial slots 33 in which the type bars are guided, and said type bars are pivoted on a wire 34 lying in a slot 35 cut in the segment 18, and said wire is secured in place by

screws 36, Figs. 1 and 3, threaded into the upper surfaces of the end parts of the segment and having broad heads which overlap the ends of the wire.

The case shift motion could be imparted either to the segment 18 or to the platen 5, but I have preferred to shift the segment. To this end said segment constitutes part of a shift frame, being supported at its ends on arms or bars 37, Fig. 1. These bars extend to the segment 18 from the rear, said bars being rigid with the cross bar 32, so that the segment 18 which constitutes the supports for the type bars and the cross bar 32 which constitutes the support for the sub-levers, both form parts of one rigid shiftable frame. Said frame also comprises arms 40 which extend backward and upward from the bar 32 and at their upper rear ends are pivoted at 41 to the stationary framework. This rigid shift frame is of such form that it is easily made as an integral casting. In the present instance the pivots 41 consist of the reduced inner ends of pins which are mounted in posts 42 where they are secured adjustably by means of set screws 43. The posts 42 project upward from parts 44 that extend inward from the rear ends of the frame bars 3, so that said posts 42 are, in effect, extensions of said frame bars.

A type rest 46, consisting of a segmental channel-shaped piece of metal with a pad 47 mounted in it, is mounted on the forward ends of arms 48 which project toward the front of the machine from the segment 18, so that said arms and the type rest constitute parts of the shiftable frame in which the type bars and sub-levers are mounted. The pad 47 is made of cork clamped in the casting 46 of sheet metal. I find that there is a distinct advantage in making this pad of cork which substance is practically noiseless when struck by the returning type bar and at the same time it is unusually free from that sort of resilience which results in rebound. Said shiftable frame may be provided with any suitable spring to assist in supporting the weight of said frame. In the present instance a spring 50 has its rear end connected with the lower part of the segment 18 and its forward end is connected with an adjusting screw 51 which passes through a comb-plate 52 which guides the key levers just back of the keyboard.

The two pivots 41 define a transverse horizontal pivotal axis about which the shift frame is adapted to swing. Said axis preferably lies, at least substantially, in the plane which also includes the axis of the platen 5 and the printing point on the front face of said platen. As said printing point in the present instance is located directly and horizontally in front of the axis of the platen, the plane above described is a hori-

zontal plane and the axis of the shift frame is situated horizontally in the rear of the platen axis. It will, of course, be understood that it is not essential that the axis of the shift frame be absolutely in this plane but there are important advantages about having it substantially so.

It will be perceived that the shift frame is readily detachable, so that in the manufacture of the machine, the type bar and sub-lever system and the links 13, can all be assembled in said frame outside of the machine and then put in place as an entirety.

In order to provide for the shift of the sub-levers 14 with the type bars, the axis of the pivots 41 is located substantially in the plane which includes the upper and lower ends of the links 13. In the present instance these links all lie substantially in the same vertical plane and, that being the case, the pivots 41 are also located in said vertical plane. Said pivots are, therefore, in the line of intersection of the vertical plane of the links 13 with the horizontal plane of the axis of the platen. It is, of course, not essential that the links 13 stand vertically nor that they all stand in the same plane but it is preferable that each of said links, when the shift frame is in its middle position, stand in such position that its longitudinal axis if prolonged would pass through the axis of said shift frame. It will be understood that this condition would be fulfilled if the links 13 stood in a vertical plane and were of different lengths, which they would be if the bar 32 were segmental instead of straight. I prefer to have the upper ends of the links 13 nearer than the printing point to the axis of the pivots 41, so that the motion of said upper ends front and back due to the case shift, is but slight.

The means for shifting the shift frame to its several positions will now be described, although it will be understood that, as far as the features already described are concerned, any suitable means can be provided for this purpose. As shown in the drawings the shift frame is normally maintained in its middle position, and two case shift keys 53 and 54 are provided, the former marked "Cap," and the latter "Fig." The key 53 is adapted to move the shift frame downward and the key 54 is adapted to move said frame upward. Said keys are mounted on the forward ends of lever arms 55 and 56, which lever arms are made of sheet metal and at their rear ends are secured to forwardly extending arms of two bell-crank 57 and 58 by means of rivets 59. Said two bell-crank 57 and 58 are pivoted side by side on a screw 60 passing through a fixed support 61 which is secured by means of adjusting screws 62 to the cross bar 21 that constitutes the support for the key lever system. Said support 61 consists of a bar or block-like piece of metal

having a transverse fulcrum rib 63 projecting from its under side and bearing against the upper surface of the bar 21. The screws 62 pass upward through the bar 21 and are threaded into the piece 61. The screw 60 can be nicely adjusted as to elevation by loosening one of the screws 62 and tightening the other.

The bell-crank 58 to which the shift key lever arm 56 is connected, has the form best shown in Fig. 2 where it will be seen that near its upper end said lever arm is formed with a curve 65 for the purpose of avoiding interference with the action of the other shift key, and above said curve the lever arm 80 is curved back upon itself in such a way as to form an inclined cam slot 66 adapted to coöperate with a follower roller 67 journaled on a pivot screw 68 which is threaded into the left-hand side bear 37 of the shift frame. 85 The construction is such that when the key 54 is depressed the upright arm of the bell-crank 58, moves toward the front of the machine and the cam slot 66 acting on the roller 67 cams the shift frame to its upper position. 90 If a printing key lever be now depressed the type bar will print from the lowermost one of the types 17, as shown in Fig. 5.

The bell-crank 57 to which the upper-case shift key 53 is connected, has an upright arm 95 formed at its upper end with a cam slot 71 adapted to coöperate with a roller 72 mounted on the screw 68 by the side of the roller 67. The two rollers are separated by a washer 73, Fig. 3, and another washer 74 is 100 situated between the roller 72 and the head of the screw 68 and serves as a guide for the lever 57. The inclination of the cam slot 71 is such that when the key 53 is depressed the shift frame is moved to its lowermost position such that if a type bar be operated it will print from the uppermost one of its types 17, as shown in Fig. 6.

When the parts are in normal position as shown in Fig. 2, the roller 72 rests on a horizontal ledge or shoulder 75 formed on the arm of the lever 57, and the roller 67 lies directly beneath a horizontal ledge or shoulder 76 on the lever 58, said shoulders constituting dwells in the respective cams. The 115 construction is such that the two rollers are in effect held between the two horizontal shoulders or dwells 75 and 76 so that motion of the shift frame either up or down from its middle position is positively prevented. 120 It will be seen, that an adjustment of the fulcrum screw 62 resulting in a bodily movement of both bell-crank 57 and 58 up or down together, adjusts the type bar segment with relation to the platen 3 for all three of 125 the positions of said segment.

In order to limit the downward motion of the keys 53 and 54, two stop screws 77 are threaded through the bar 21 beneath the arms 57, 58. Said stop screws can be ad- 130

justed up and down and retained in ad-
justed position by set screws 78.

A space key 80 is here shown mounted on
the forward ends of lever arms 81 which at
5 their rear ends are secured to a rock shaft 82
pivoted at its ends in the frame plates 20
of the detachable frame. Near the middle
of the rock shaft 82 an arm 83 is secured
which projects toward the rear of the ma-
chine parallel with the key levers 11. In
10 the machine a suitable universal bar is
mounted just above this arm 83 and the rear
ends of the key levers, and said universal bar
operates the escapement and other devices.

15 The shiftable features of the type action
and case shift mechanism are not claimed
herein, but are made the subject-matter of
a divisional application filed Feb. 5, 1914,
Sr. No. 816,757.

20 Various changes can be made in the de-
tails of construction and arrangement with-
out departing from my invention.

What I claim as new and desire to secure
by Letters Patent, is:—

25 1. In a front strike typewriting machine,
the combination of a front strike type bar,
a link extending from said type bar toward
the rear of the machine, a sub-lever having
an arm extending downward at an inclina-
30 tion toward the front of the machine and
connected with said link, and said sub-lever
having another arm extending toward the
rear, a key lever of the first order and a
push link connected with the rear end of
35 said key lever and with said rearwardly ex-
tending arm of the sub-lever.

2. In a front strike typewriting machine,
the combination of a series of front strike
type bars, links extending from said type
40 bars toward the rear of the machine, a series
of sub-levers pivoted in a straight row and
having arms extending downward and to-
ward the front of the machine and connected
with said links, said sub-levers also having
45 arms extending toward the rear of the ma-
chine, a series of key levers of the first order,
and push links connecting the rear ends of
said key levers with said rearwardly extend-
ing arms.

50 3. In a front strike typewriting machine,
the combination of a series of type bars, a
series of sub-levers connected with said type
bars, a series of substantially straight key
levers of the first order each having its rear
55 end connected by an upright link with one

of said sub-levers, and keys mounted on said
key levers in a plurality of rows at different
elevations, the fulcrums of the key levers be-
ing arranged in transverse tiers, the lowest
tier being nearest the front of the machine, 60
and the highest tier being nearest the rear of
the machine, the respective distances of said
fulcrums from the back of the machine be-
ing such as to give to the several rows of
keys equal leverages on said sub-levers and 65
the keys that are situated at a higher eleva-
tion having the fulcrums of their key le-
vers at a greater elevation than the fulcrums
of lower keys.

4. In a front strike typewriting machine, 70
the combination of a series of front strike
type bars pivoted in a segment, a series of
sub-levers in the rear of said series of type
bars, said sub-levers having arms extending
from the pivots of said levers downward at 75
an inclination toward the front of the ma-
chine, links connecting said arms with said
type bars, those links that connect with type
bars near the middle of the system extend-
ing forward at a downward inclination and 80
those links that connect with type bars near
the ends of the system extending toward the
front of the machine at an upward inclina-
tion whereby said sub-levers have a higher
initial leverage on the type bars near the 85
middle of the system than those near the end
of the system and impart to said middle
type bars a greater acceleration.

5. In a front strike typewriting machine,
the combination of a series of front strike 90
type bars pivoted in a segment, a series of
sub-levers pivoted in a straight line and hav-
ing arms extending from their pivots and
downward at an inclination toward said seg-
ment, links connecting said sub-levers with 95
said type bars, some of said links extending
from said sub-levers to said type bars at an
upward inclination and others at a down-
ward inclination, a series of key levers, and
links connecting said key levers with said 100
sub-levers in such fashion as to afford an
acceleration of said sub-levers.

Signed at the borough of Manhattan, city
of New York, in the county of New York
and State of New York, this 24th day of 105
April, A. D. 1913.
